Specification of Letters Patent. Patented May 13, 1919.

Application filed December 26, 1917. Serial No. 208,832.

To all whom it may concern:

Be it known that we, FRANK A. LEE and FRANK G. ROSE, citizens of the United States, and residents of Cincinnati, in the county of Hamilton and State of Ohio, and Dayton, in the county of Campbell and State of Kentucky, respectively, have invented certain new and useful Improvements in Phonographs, of which the following is a specification.

Our invention relates to megaphones for phonographs or graphophones.

The object of our invention is to intercept and throw back at varying angles, the sound-waves which would otherwise pass directly from the throat of the megaphone directly out through the mouth thereof, so that these waves strike either against the sides of the megaphone or the throat thereof, and, thus traveling a longer distance and striking vibrating surfaces, are enriched and clarified in tone. The further object of our invention is to take advantage of the vibration of the surfaces against which the sound-waves strike to further enrich and clarify the tone of the apparatus.

Our invention consists in the combination of parts and in the details of construction and arrangement of parts as will herein-after be more fully described and claimed.

In the drawings:

Figure 1 is a general perspective view of a phonograph provided with our improvement;

Fig. 2 is a longitudinal vertical section of the megaphone and throat, the latter being modified from that shown in Fig. 1;

Fig. 3 is a detail perspective view of our improvement, as shown in Fig. 1, but with another modified throat;

Fig. 4 is a section similar to Fig. 2, but showing the throat of Fig. 1, and showing a plurality of deflectors in the megaphone; and

Figs. 5 and 6 illustrate modified deflectors.

For the purpose of illustrating our invention, there is shown in Fig. 1 a phonograph of usual construction, comprising a casing 1 which carries on its top the turn-table 2, which may be revolved by a suitable motor (not shown) under the top of the casing, and which turn-table 2 carries the record 3 thereon, receiving the stylus 4 carried in suitable means on the sound-box 5, which is mounted on the sound-arm 6, which

is fixed on the top of the base 1 by a suitable pedestal 7 at the rear of the turn-table, and being hollow and gradually increasing in interior area down to the opening 8 through the top of the base 1 under the pedestal 7. All of this construction is well-known, and, also, in Fig. 1, the throat 9 is of the usual form curving downwardly and forwardly to enter the smaller rear end of the megaphone 10, the large end of which opens through the front of the casing 1 which has an apertured door 11, only part of which is shown.

Ordinarily, the sound-waves traveling from the diaphragm in the sound-box 5 backward and downward through the sound-arm 6 and its hollow pedestal 7 and aperture 8, pass from there downwardly and forwardly through the throat 9 and directly out through the megaphone 10 and through the apertured door 11. The sound-arm, throat and megaphone all being of gradually increasing internal area, the sound-waves are amplified, but at the same time the combined length of these passages being considerable, the waves are also confined and somewhat intensified. Also, due to the curvature of the sound-arm and throat, there are some deflections of the sound-waves in their passage therethrough with the result that some of them will be directed against the sides of the megaphone, causing these to vibrate, and causing the sound-waves to travel longer distances. We have discovered that these influences on the sound-waves are in the direction of enriching and clarifying the tones. Accordingly, we provide in our present invention for intercepting these waves in the megaphone, so that they are caused to strike the sides of the megaphone or back in the sides of the throat additionally, and to also intercept such waves as, in their emergence from the throat into the megaphone, would not strike the sides of the megaphone at all, but would be thrown directly out therefrom without being materially subjected to these influences which we have discovered to have a beneficial effect.

As we prefer to embody our invention for this purpose, we provide an accumulator or deflector 12, which consists of a relatively thin element of extended area placed approximately in the center of cross-section of the megaphone at a suitable point along the length thereof, and lying across the mega-

phone substantially at right angles to its length. This accumulator or deflector is preferably somewhat more than half the dimension of cross-section of the megaphone 5 in any direction, so that it leaves one relatively narrow open space all around its edge between the edge and the adjacent walls of the megaphone. It is preferably made to approximate in shape the shape of cross-section 10 of the megaphone. For instance, as here shown, the cross-section of the megaphone is rectangular, somewhat wider than it is high; and the accumulator or deflector 12 is of proportionate width and height, but preferably 15 having its corners rounded. This rounding of the corners is to facilitate the manufacture, and, possibly, improve the appearance of the element 12. As shown in Figs. 1 to 4, inclusive, the element 12 has its 20 inner side 13 made approximately concave, and to preserve the desired thinness of the element, the outer side 14 is made correspondingly convex; while to preserve the strength thereof, the element is provided 25 with a comparatively thick rim 15 entirely around its edge. The operations necessary on the two sides of the element are more conveniently performed with the corners rounded, as above described. Otherwise, the 30 corners might be square without materially altering the effect of the element upon the sound-waves. Of course, should the megaphone be made with the corners of its cross-section rounded, the rounding of the corners 35 of the element 12 would be also for the purpose of making it conform to the megaphone cross-section; it being understood that it is always desirable to have the narrow open space around the deflector or accumulator of 40 about uniform width throughout its length therearound. The shapes of the megaphones and the element 12 may vary; but the oblong shape here shown is deemed preferable, as the practical construction nearest approaching 45 the shape of an ellipse, which is considered the best shape of cross-section for a sound-conductor to be.

Also, it will be understood, that the deflector or accumulator 12 may be located at 50 any desired distance from the larger open end of the megaphone, depending upon the number of deflections to be imparted to the sound-waves and the desired length of increased travel desired to be imparted to the 55 sound-waves by such deflections. As herein shown, the deflector or accumulator is located close to the large front open end of the megaphone.

To support the accumulator or deflector 60 12 in the proper position across the central part of the megaphone cross-section, without unduly obstructing the space therearound next to the megaphone walls, we prefer to provide relatively thin posts 16 above and 65 below and extending vertically upward and

downward from the edges of the element 12 and at opposite sides extending horizontally outward from the edges of the element 12 and fixed in suitable small pedestals 17 which are attached to the walls of the megaphone. 70 These posts 16 are attached to the element 12 by being inserted into holes bored in the edges of the element, and are similarly attached to their pedestals 17, but the pedestals 17 are preferably merely secured to the surface of the megaphone wall in each instance, so as not to unduly break up the continuity of structure of the megaphone. 75

While these posts 16 serve to support the deflector or accumulator 12, they also act as 80 sound-posts adapted to impart the vibrations of the accumulator or deflector 12 to the walls of the megaphone, and thus constituting the entire megaphone or accumulator and deflector structure a sound device somewhat upon the principle of the shell of a stringed musical instrument. With this purpose in view, we prefer to construct the accumulator or deflector 12 of wood (preferably spruce, and other woods in combination 85 therewith) and to give it its approximately concavo-convex form by cutting it from solid wood, rather than by steaming and bending the wood, which tends to destroy the natural properties of the wood for beneficially affecting sound-waves impinging thereon or set up by the vibration thereof. 90

With the modified throat 9' shown in Fig. 2, which throat, in its final forward extension to the rear end of the megaphone 10, curves slightly upward, additional deflections are afforded in this throat; and how the deflector or accumulator 12 co-operates in this way, causing a greatly increased length of travel of the sound-waves by successive 100 deflections against the megaphone walls, is indicated by the broken lines and arrows in this figure. 105

In Fig. 3 is shown another modified throat 9''. This throat is disclosed and claimed in 110 our co-pending application filed December 26, 1917, Serial No. 208,831. This throat is provided with a suitable means for joining it with the under side of the top of the casting 1 to communicate with the interior of 115 the sound-arm 6 through the pedestal 7 thereof and the aperture 8 through the casting top, and curves downwardly and to the right (supposing one to be facing the apparatus) this first curve 18 being comparatively abrupt, and then continues to the right and downwardly, and to the left in a much less abrupt curve 19, then to the left and upward and to the right again in another large curve 20, passing close under the 120 first curve 18 and then downward approximately in the center of the apparatus in a curve 21, and then curving downwardly and forwardly and slightly upwardly in a final curve 22 where the throat communicates 125 130

with the smaller rear end of the megaphone 10. This throat, in addition to having the successive curves described, is preferably of constantly increasing interior area from its 5 beginning to its end, and preferably has its curved walls sawed out of solid blocks of wood, rather than steamed and bent, for the reasons just given in describing the preferred construction of the accumulator or 10 deflector 12. It will be understood that this modified throat and the megaphone with the accumulator or deflector 12 provided, as described in connection with Fig. 1, would be 15 mounted in the phonograph as shown in Fig. 1.

It will be seen that this throat 9" is of 20 greatly increased length; in fact, being about four times as long as the throat 9 or 9'; and, furthermore, the number of deflections of the sound-waves therein is greatly increased; both of which circumstances tend to amplify, intensify, enrichen the quality of and clarify the sound-waves, so that they reproduce with more fidelity the actual quality 25 of the sound-waves imparted from the phonograph record to the diaphragm. The result of using such a throat is to have the sound-waves emerge into the megaphone in a great variety of directions, on account of 30 the varying initial directions which the sound-waves had, because of being produced by the diaphragm vibrating in various positions, accordingly as succeeding vibrations begin before preceding ones are completed; 35 with the result that these sound-waves cross and re-cross the megaphone 10 in complex form, which is, of course, not adequately indicated by the mere tracing of the path of one sound-wave, as is approximately done in 40 Fig. 2.

Moreover, the final curvature of the throat where it enters the megaphone being upward, as in Fig. 2, this effect is combined with that of the greatly lengthened and suc- 45 cessively curved throat.

The result is that a greatly increased number of deflections of the sound-waves is produced by the accumulator or deflector 12 as it receives these waves in their complex 50 crossing and recrossing of the megaphone, directing them back against the megaphone walls and the interior of the throat, and causing a new succession of crossings and recrossings, until the wave finally emerges 55 through the open space around the element 12 greatly enriched and clarified in tone, as a result of having traveled the increased distances, and having repeatedly impinged upon the vibrating surfaces of the mega- 60 phone, throat and element 12.

It is found in practice, with the use of our invention, that through such method of travel of the sound-waves through the megaphone, as a result of action of the accumulator or deflector, either with or without the 65

greatly lengthened and curved throat shown in Fig. 3, the waves are not only amplified and intensified, but are made richer in quality and greatly clarified, with the result that they reproduce with greater fidelity than we 70 have heretofore known, the actual quality of the sounds as they were originally produced, and as they are, of course, expected to be reproduced by a phonograph. We have found in practice that our improved 75 phonograph, as herein described, is capable, for instance, of rendering a satisfactory reproduction of piano music which has always presented great difficulty of reproduction heretofore. Moreover, due to this increased 80 clearness caused by the complex travel of the sound-waves, as well as to the greater intensity derived from the accumulation, due to the action of the deflector or accumulator 12, the phonograph provided with our invention, will, with the usual record and soundbox, and reproducing practically any kind of music or other production, afford a more satisfactory reproduction to a hearer at a considerable distance from the apparatus. 85 Also, on account of the greater intensity, somewhat greater amplification is permissible, and this is well provided by the greatly increased length of the throat 9" when this is used in conjunction with the accumulator 90 or deflector. This somewhat increased amplification, of course, also makes the apparatus audible at a greater distance. 95

In the modification shown in Fig. 4, the throat of Fig. 1 is shown in section; but it 10 will be understood that either other throat may be used. The modification consists in providing an additional accumulator or deflector 12' some distance farther inward in the megaphone 10 and being constructed the 105 same as the larger one 12 farther outward; but, of course, being correspondingly smaller in accordance with the decreased cross-section of the megaphone where this additional element 12' is located. The result of this 110 provision is to increase the number of deflections of a sound-wave, since many waves, after having been deflected, due to the action of the first or inner element 12' are again started through a series of deflections, either 115 against the megaphone walls or the outer side of the inner element 12', by striking the outer element 12, and finally emerging from the megaphone.

In Fig. 5, the element 12^a has its inner side 120 13^a plane instead of approximately concave, and, in accordance therewith, the outer side 14^a is also plane. As shown in Fig. 6, the element 12^b has its approximately convex side 14^b inward, and its approximately con- 125 cave side 13^b out to the front of the megaphone. The result of either one of these modifications is to cause different deflections of the sound-waves, the general results, both as to increased length and complexity of 130

travel of the waves, and the effects due to vibration of the elements and of the megaphone walls, being similar to those of the preceding examples, as fully described.

5. It will be understood that other minor modifications are within the scope of our invention, which having been fully set forth, is defined in the following claims:

1. In a sound-producing instrument, a megaphone flaring forwardly, and a throat leading downwardly and forwardly into the rear end of said megaphone, an element rigidly mounted across the central part of the interior cross-section of said megaphone 10 in upright position, and spaced away from the upper, lower and lateral walls of said megaphone, said megaphone being freely open from the space around the deflector to the outlet end of the megaphone, and said 15 deflector being adapted to intercept sound-waves as they pass from said throat and reflect them back toward said throat, for the purposes set forth.

2. In a sound-producing instrument, a megaphone flaring forwardly, and a throat to conduct sound-waves to said megaphone, said throat extending downward and then curving upwardly near its junction with said megaphone, and an element extending 20 partly across the interior of said megaphone in upright position to intercept said sound-waves as they pass from said upwardly curving throat and reflect them back toward said throat, for the purposes set forth.

3. In a sound-producing instrument, a megaphone flaring forwardly and receiving sound-waves, a deflector consisting of a relatively thin element lying across the central part of the interior cross-section of said

megaphone, with its inner side fully exposed 40 to sound-wave impacts throughout its extent, from its center to its periphery, and a relatively thick rim around and rigidly secured to said element, and a sound-post comprising a relatively thin part rigidly secured 45 to said rim, and a pedestal of relatively extended base area rigidly secured to said thin part and rigidly secured to one of the walls of said megaphone to support said deflector, and to transmit vibrations of the deflector to said walls, or of said walls to said deflector, for the purposes set forth. 50

4. In a sound-producing instrument, a megaphone flaring forwardly and receiving sound-waves, a deflector consisting of a relatively thin element lying across the central part of the interior cross-section of said megaphone with its inner side fully exposed to sound-wave impacts throughout its extent, from its center to its periphery, and of approximately concavo-convex form, whereby a curved surface is presented to the sound-waves as they come through said megaphone, and a relatively thick rim around and rigidly secured to said element, 60 and a sound-post comprising a relatively thin part rigidly secured to said rim, and a pedestal of relatively extended base area rigidly secured to said thin part and to one of the walls of said megaphone to support said deflector, and to transmit vibrations of the deflector to said walls, or of said walls to said deflector, for the purposes set forth. 65
